Primary Examiner — Jerry Shuan-Hua Hsu(74) *Attorney, Agent, or Firm* — Sisson & Banyas, Attorneys at Law, LLC; Jeffrey J. Banyas(57) **CLAIM**

The ornamental design for a traction board mount as shown and described.

DESCRIPTION

FIG. 1 is a top, front perspective view of a traction board mount;

FIG. 2 is a front view thereof;

FIG. 3 is a rear view thereof;

FIG. 4 is a right-side view thereof;

FIG. 5 is a left-side view thereof;

FIG. 6 is a top view thereof;

FIG. 7 is a bottom view thereof; and,

FIG. 8 is an exploded top, rear perspective view shown in a condition of use.

The dash-dash broken lines in FIGS. 1 through 7 depict portions of the traction board mount that form no part of the claimed design. The dash-dot broken lines in FIG. 8 showing a car and attachments depict environmental structure that forms no part of the claimed design. The dash-dot broken lines in FIG. 8 depicting alignment lines of the exploded portions of the view form no part of the claimed design.
